UNITED STATES PATENT OFFICE.

SAMUEL G. CAMP, OF PHILADELPHIA, PENNSYLVANIA, ASSIGNOR OF ONE-HALF TO
THOMAS D. HILL, OF PHILADELPHIA, PENNSYLVANIA.

CHANDELIER.

1,031,241.

Specification of Letters Patent.

Patented July 2, 1912.

Application filed February 28, 1912. Serial No. 680,455.

To all whom it may concern:

Be it known that I, SAMUEL G. CAMP, a citizen of the United States, residing at Philadelphia, in the county of Philadelphia and State of Pennsylvania, have invented certain new and useful Improvements in Chandeliers, of which the following is a specification.

My invention relates to improvements in chandeliers, and more particularly to an improved chandelier for electric lights, the object of the invention being to provide a chandelier which may be folded and telescoped so as to enable the same to be packed in a relatively small space for shipment.

A further object is to provide a chandelier which is capable of adjustment so that there is no necessity for making the same in a great many different sizes, but permit the builder or user to adjust the chandelier in accordance with the height of the ceiling and the desired location with relation to the floor.

With these and other objects in view, the invention consists in certain novel features of construction and combinations and arrangements of parts, as will be more fully hereinafter described and pointed out in the claims.

In the accompanying drawings: Figure 1, is a view in longitudinal section partly in elevation illustrating my improvements, one arm of the chandelier being in normal position and the other arm folded. Fig. 2, is a view in elevation illustrating the clamp at the lower end of the stem. Fig. 3, is a view in section on the line 3—3 of Fig. 2, and Fig. 4, in a view in section on the line 4—4 of Fig. 2.

1, represents the tubular stem of my improved chandelier on the upper end of which a screw-threaded plug 2 is secured, and is adapted to screw in a bracket 3 fixed to the ceiling 4. In this stem 1, a tube 5 telescopes, and is clamped at vertical adjustment in the same by means of a clamp 6 in the lower end of the stem. This clamp is provided with lugs 6^a which project through an opening 6^b in the stem 1, and are bent back securing the clamp in the stem. Parallel ears 7 are formed on the clamp, said ears perforated to receive a bolt 8 having a nut 9 thereon, whereby the clamp may be operated to clamp or release tube 5. The lower end of this tube 5 has a tubular plug

10 fixed therein, and into which a threaded coupling 11 is screwed. The lower end of this coupling 11 is screwed into a horizontal circular head 12 into which horizontal tubes 13 are secured by means of screws 14. These screws 14 are positioned in threaded openings in the tubular head 12, and securely lock tubes 13 in the head. The outer ends of these tubes 13 are preferably up-set as shown at 15 against the outer face of a ring 16, and this ring 16 is engaged by cup shaped sections 17 and 18 respectively to form an ornamental center to the chandelier, which incloses the head and other parts tending to disfigure the chandelier. The lower cup 18 is held in place by means of a knob 19 screwed onto the lower end of a yoke 20, which is screwed into a socket in head 12, while the clamp 6 is inclosed in its own cup 6^c which permits access thereto at any time desired.

In the tubes 13, the tubular arms 21 of the chandelier telescope, and are normally secured therein by means of screws 22 which are threaded in rings 23 fixed to tubes 13, and jamming against the tubular arms 21. In Fig. 1, it will be seen that one of these arms 21 is shown in its normal position, while the other arm 21 has been drawn out of its tube 13, and is folded back toward the stem 1. This movement of the arm 21 is permitted by reason of the slack in the electric wires 24, said wires bulging down through the hollow head 12, and it is to be understood that in constructing the chandelier, the same will be properly wired and the necessary connections made, while sufficient slack will be allowed to permit the arms to be folded back and the chandelier to be adjusted vertically so as to perform all its intended functions.

I would have it understood that while my improved chandelier is capable of being packed in a relatively small space by reason of the fact that the stem may be shortened longitudinally, and the arms 21 folded back beside the stem, the chandelier is not intended to be adjustable in the sense that it is to be raised and lowered by the occupant of a room. It is made adjustable, so that it might not only economize in the expenses of shipment, but also may be made so as to be utilized in any room. It is of course to be adjusted by the workman who puts the chandelier in place, and after it is once ad-

justed by him, it is not intended to be re-adjusted or to be moved in any way by the occupant of the house.

The tubular arms 21 are of such an external diameter as to snugly fit tubes 13, so that when they are forced into the tubes and secured by the screws 22, the device will have no appearance whatever of hinged arms, and I would have it understood that 10 the arms are not hinged, but are telescoped, and the folding movement is permitted by the slack in the electric wire.

Various slight changes might be made in the general form and arrangement of parts 15 described without departing from my invention, and hence I do not limit myself to the precise details set forth, but consider myself at liberty to make such changes and alterations as fairly fall within the spirit 20 and scope of the appended claims.

Having thus described my invention, what I claim as new and desire to secure by Letters Patent is:

1. In a chandelier, the combination with 25 a longitudinally adjustable stem comprising an inner and an outer tube and means securing said tubes together, of a circular head secured to the lower end of the tubular stem, a ring having openings therein, tubes 30 secured at their ends to said head and at their outer ends to said openings in the ring, tubular arms constructed to telescope in said tubes, and screws projected through the tubes and securing said tubular arms in the 35 tubes, substantially as described.

2. In a chandelier, the combination with 40 a longitudinally adjustable stem comprising an inner and an outer tube and means securing said tubes together, of a circular head secured to the lower end of the tubular stem, a ring having openings therein, tubes secured at their ends to said head and at their outer ends to said openings in the 45 ring, tubular arms constructed to telescope in said tubes, screws projected through the tubes bearing against the arms, and electric wires in said stem, head, tubes, and arms, substantially as described.

3. In a chandelier, the combination with 50 a longitudinally adjustable stem, comprising an inner and an outer tube and means securing said tubes together, of a circular head secured to the lower end of the tubular stem, a ring having openings therein, tubes secured at their ends to said head and at their outer ends to said openings in the 55

ring, tubular arms constructed to telescope in said tubes, screws projected through the tubes bearing against the arms, and electric wires in said stem, head, tubes, and arms, 60 cups secured above and below the ring and engaging the same forming an inclosure, and said wires having slack therein projecting through the ring and confined within the said inclosure, substantially as described. 65

4. A chandelier comprising a tubular stem, consisting of an outer tube, and an inner tube movable relative to each other, a clamp on the lower end of the outer tube constructed to clamp the tubes against independent movement, a circular head secured to the lower end of the inner tube, a ring having openings therein, tubes secured at their inner ends in said head and at their outer ends in said openings in the ring, tubular arms constructed to telescope in said tubes, screws in said tubes bearing against the arms, and electric wires in said stem, head, tubes, and arms having sufficient slack to allow said arms to be drawn out of the 70 tubes and folded back toward the same, substantially as described.

5. A chandelier comprising a tubular stem, consisting of an outer tube, and an inner tube movable relative to each other, 85 a clamp on the lower end of the outer tube, constructed to clamp the tubes against independent movement, a circular head secured to the lower end of the inner tube, a ring having openings therein, tubes secured 90 at their inner ends in said head and at their outer ends in said openings in the ring, tubular arms constructed to telescope in said tubes, screws in said tubes bearing against the arms, and electric wires in said stem, 95 head, tubes, and arms having sufficient slack to allow said arms to be drawn out of the tubes and folded back toward the same, cup shaped ornamental sections above and below the ring and engaging the ring, a rod 100 secured to the tubular head and extending through the lower shaped section, and a knob screwed onto the lower end of said rod against said section, substantially as described.

In testimony whereof I have signed my name to this specification in the presence of two subscribing witnesses.

SAMUEL G. CAMP.
